UNITED STATES PATENT OFFICE.

JAMES S. BARRON, OF NEW YORK, N. Y.

DESIGN FOR A COIN-TRAY.

No. 38,718.

Specification for Design.

Patented Aug. 6, 1907.

Application filed April 26, 1907. Serial No. 370,536. Term of patent 3½ years.

To all whom it may concern:

Be it known that I, JAMES S. BARRON, a citizen of the United States, residing in the city, county, and State of New York, have invented a new, original, and ornamental Design for a Coin-Tray, of which the following is a specification, reference being had to the accompanying drawing, forming part thereof.

Figure 1 is a plan view of a coin-tray,

showing my new design, and Fig. 2 is a perspective view thereof. Fig. 3 is an edge view of the coin tray showing my new design.

I claim:

The ornamental design for a coin-tray, as shown.

JAMES S. BARRON.
